UNITED STATES PATENT OFFICE.

HERMAN HOLLERITH, OF WASHINGTON, DISTRICT OF COLUMBIA.

APPARATUS FOR USE IN TABULATING SYSTEMS.

1,109,841.

Specification of Letters Patent.

Patented Sept. 8, 1914.

Application filed June 20, 1913. Serial No. 774,924.

To all whom it may concern:

Be it known that I, HERMAN HOLLERITH, of Washington, in the District of Columbia, have invented certain new and useful Improvements in Apparatus for Use in Tabulating Systems; and I do hereby declare the following to be a full, clear, and exact description of the invention, such as will enable others skilled in the art to which it appertains to make and use the same.

The primary object of this invention is to provide in a tabulating system means for recording the numbers indicated by a series of registering devices; and a further object is to effect such recording synchronously with the return of the registering means to initial position.

The invention is especially adapted for use in connection with the class of record-cards employed in the Hollerith tabulating system, such cards having index-point positions which are preferably indicated by punched holes located on each particular record-card in accordance with the data which that card represents.

By means of my present invention the recording mechanism will be automatically controlled by means operated synchronously with the actuation of the registering means, and the actual record will be made as such registering means and controlling means are returned to their initial positions.

In the accompanying drawings, Figure 1 shows, diagrammatically, a portion of a typical but not an essential form of apparatus embodying my invention. Fig. 2 shows, diagrammatically, another portion of the apparatus. Fig. 3 is a plan view. Fig. 4 is a vertical longitudinal sectional view on line 4—4, Fig. 3. Figs. 5 and 6 show details of the machine. Fig. 7 is a face view of a record-card.

The record-cards are preferably placed on edge, with the cipher at the top, upon a platform 1, and are fed, one by one, to the action of record-actuated contacts by a reciprocating cross-head 2 and feed-rollers 3, in gear with the main operating shaft. As the feeding mechanism shown is substantially similar to that described in my U. S. Letters Patent No. 945,236, further description thereof is unnecessary. Conducting brushes 4, 4^a and 4^b, are normally in contact with plates 5, 5^a, and 5^b, insulated from each other, but the brushes and their contact plates are separated when a card is fed be-

tween them. Each brush and its respective plate form a pair of electrical contacts, which are actuated or permitted to come together and move apart, by the record. When a card is fed between the brushes and the contact plates, the index-point positions of each column of the group to which the contact brushes apply, are presented successively to the brushes or record-actuated devices, and when the punched hole in a column registers with the brush of that column, the brush will contact with its complementary member, and an electrical contact will be established momentarily and the corresponding registering device will be operated in the manner well known in connection with the tabulating registers of the Hollerith system, and according to my present invention means for controlling the recording mechanism will likewise be operated in synchronism with the registering device. The brushes are mounted on a common plate 6 which is energized when a punched hole registers with a brush, being in circuit with a battery 7.

I do not deem it necessary to describe the various details employed in connection with the tabulating registers, all of which are well understood by those skilled in the art; it will suffice to point out that the circuit, which includes the registering device, during the intervals between the moving cards is opened, but is closed just as the edge of an advancing card passes between the brushes and the plates, and remains closed until just as the card is about to pass from under the brushes. I have shown in Fig. 2 contacts 8 controlled by a cam 9 for accomplishing the result just stated.

The several contact plates 5, 5^a and 5^b are separately connected in circuit with relay magnets 12, 12^a and 12^b, having circuit closing armatures 13, 13^a and 13^b, said magnets being in circuit with controlling magnets 14, 14^a and 14^b, whose armatures are in the form of spring-held levers 15 for controlling clutches 16 splined so as to slide on a shaft 17 and turn therewith. On this shaft are located three registering wheels 18, 18^a and 18^b, which are intended to illustrate a typical form of registering apparatus; but their number may, of course, be varied, as desired, that is to say, the number of registering devices will correspond to the number of groups of a record-card. The wheel 18 indicates units; wheel 18^a tens; and the wheel

18^h hundreds corresponding to a series of columns in a single group, and these wheels are suitably supported so that the turning movement of the shaft 17 will not actuate them until they are brought into positive connection therewith through the actuation of the clutches.

According to my present invention, means for controlling the recording mechanism is actuated synchronously with, and to the same extent as, the registering devices, and as such recording mechanism is operated to record the total of the registering devices the latter are returned to zero ready for the next operation.

The particular construction of the recording mechanism and its controlling means may be widely varied. I have shown the registering devices in the form of gear-wheels 20 loosely mounted on a normally idle re-setting shaft 21. Each of the wheels 20 has lateral projections 22 extending therefrom and which correspond to the nine digits and the cipher, as indicated in Fig. 1, and in addition thereto each wheel has an extra projection 23 between the lugs corresponding to the digit 9 and the cipher. Each wheel 20 carries a spring-held pawl or tooth 24 which is designed to be engaged by a shoulder or cut-out 25 of shaft 21 so that when the latter is rotated all of the wheels 20 may be returned to zero. When in this latter position a circuit 26 is closed through contacts 27 as shown by the position of the contacts controlled by the unit wheel 20 in the diagrammatic view, Fig. 1. The contacts are controlled by pivoted arms 28 (Fig. 4) which in turn are controlled by projections 22, 23. The contacts 27 of the several elements 20 are all within the circuit 26 which includes a series of relay magnets 30, 30^a and 30^b, with corresponding armatures, and a second series of control magnets 31, 31^a and 31^b, the armatures of which actuate pawls 32 which are designed to engage and hold the type-carrying members of the recording apparatus.

According to the means shown the recording apparatus comprises a series of type-carrying members 35 each of which is preferably in the form of a double sector loosely mounted on a common shaft 36 upon which they are designed to reciprocate, being moved in one direction, counter-clockwise, by springs 37 and in their opposite directions by a bail 38 which is reciprocated on shaft 36, said bail being extended through arcural slots 39 in the several sectors. On their outer edges these sectors carry type ranging from 0 to 9, while their inner edges have a corresponding number of ratchet teeth 40, which teeth are designed to be engaged by pawls 32, the movement of any of the several type-carrying members being ar-

rested simultaneously with the closing of the circuit through the respective contact 27. The shaft 36 carries a sprocket-wheel 41 which is engaged by a belt 42 which also engages a sprocket wheel on the re-setting 70 shaft 21. This belt is driven by a sprocket-wheel 43 on an operating shaft 44, and said wheel 43 is so proportioned to the sprocket-wheel on shaft 21 that the latter will make two revolutions to one of the former. When 75 it is desired to re-set the registering device and to record the total represented thereby the circuit 26 is closed, first, through a temporary contact 45, and then through a permanent contact 46, and as the respective 80 magnets of the several elements 20 are energized through the closing of the circuit through the respective contacts 27, the type-carrying sectors 35 will be arrested so that the numbers printed thereby will correspond 85 to the total represented by the registering device. Although in practice the operation of the machine will be wholly automatic, depending simply upon the manual closing of the circuit through contacts 45, in order 90 to initiate the operation, in the present instance I have indicated the operating shaft 44 as having a handle 50 which is normally held locked by a lever 51, the releasing of which closes the circuit through contacts 45, 95 and immediately thereafter, as soon as the machine is set in operation by the revolution of shaft 44, contacts 46 are closed before the circuit is broken through the contacts 45, said contacts 46 being controlled by a 100 constantly-revolving cam 52 which travels in synchronism with the operating shaft 44. The circuit is held closed through contacts 46 while cam 52 and shaft 44 make one-half 105 of a revolution. During this half-revolution the bail 38 of the type-carrying members completes its movement in a counter-clockwise direction so that the segments may move under the influence of their springs 37. At the completion of this movement of bail 110 38 the electric circuit is broken through contacts 46 and the printing operation is performed by a striker 60 forcing a strip of paper 61 against the inking ribbon 62 passed between the paper and the type. During 115 the second half of the revolution of the operating shaft 44 the bail 38 returns the type-carrying segments to their initial positions, but both contacts 45 and 46 being open there 120 is no electric circuit, and hence the pawls 32 will not drag over the teeth 40.

The means for operating the bail 38 is more clearly indicated in Fig. 5. Segmental rack-teeth 65 of the bail mesh with toothed segments 66 carried by a shaft 67 which is reciprocated through the instrumentality of a cam 68 and a spring 69 acting on an arm 70 carrying a roller 71 with which the cam engages.

Any suitable means may be employed for 130

operating the striker 60. As shown in Fig. 6 this is accomplished by cams 75 on shaft 36 engaging the rollers of levers 76 on which the striker is mounted.

5 I have not shown means for feeding the paper or actuating the inking ribbon, since any suitable or preferred means may be employed for these purposes, it only being necessary that the paper be intermittently fed 10 so as to receive the imprint of the aligned type of the type-carrying members.

Each of the type-carrying members is provided with a pivoted tooth 80 which is immediately adjacent to the tooth 40 which 15 corresponds to the cipher, and this pivoted tooth has a laterally extending lug 81 which projects into a cam groove 83 in the next higher type-carrying member. The purpose of this is to prevent the cipher on an unac- 20 tuated type-carrying member from being recorded. In other words, the pivoted tooth of the units type-carrying member will be drawn out of the way of the pawl 32 by the groove in the tens type-carrying member, 25 and that of the latter by the hundreds member. When the additional lugs 23 of controlling elements 20 close the circuit through contacts 27 the respective pawls 32 will engage teeth 80 of the type-carrying members 30 so as to prevent any imprint of any of the type carried thereby and hold such members from moving under the influence of their springs 37 unless the next higher member has been moved by its spring, whereupon, if 35 the pivoted tooth be drawn out of the way of the pawl 32 the member will move until arrested by such pawl engaging that one of the teeth 40 corresponding to the member represented by the respective registering 40 element.

In operation, the cards are fed one at a time from the platform and are caused to be passed between the brushes and their contact plates. As a circuit is closed through 45 the index point position of any one of the columns of the card the respective registering device will be operated, and through it the respective registering mechanism controlling element 20 will be moved to a cor- 50 responding extent. After the card has passed through the machine, the circuit 26 is closed through contacts 45, and also through contacts 46 as shaft 44 is rotated, and during the first half of such rotation 55 the bail moves counter-clockwise and the several type-carrying members are arrested as their magnets are energized through the closing of contacts 27, which closing imme- 60 diately follows the initial movement of any one of the controlling elements 20 as they are returned to their starting points by the resetting shaft 21. All this, as well as the printing of the total, is accomplished dur- 65 ing the first half of the revolution of the operating shaft 44, and during the second

half of such revolution the type-carrying members are returned to their starting points by the reversed movement of the bail.

In Fig. 1 I have shown the several controlling members 20 of the recording mechanism in the positions they occupy when the total of the registering device is 280. It will be noted that the projections corresponding to numerals 2 and 8, and the cipher 0 are in position to close the circuit through the respective contacts 27 as soon as each of the members 20 is moved by the re-setting shaft 21. Inasmuch as the type-carrying members are moved in synchronism 80 with the actuation of the re-setting shaft 21, the several type-carrying members will be arrested so that the number recorded on the paper will correspond to the total represented by the registering device, namely, 85 280.

While I have shown and described electrically-operated means for effecting the control of the apparatus, yet it is not my intention to restrict my invention to the employment of electricity, since other equivalent means may be employed instead of an electric circuit or circuits and electrically operated devices; but I consider electricity to be the most advantageous agent and have 90 therefore selected, for the purpose of description, an electrically-operated apparatus, and in this connection it is to be understood that where electricity is employed as an actuating or controlling agent the apparatus 95 may be arranged for operation either on open or closed circuits.

I claim as my invention:

1. In apparatus of the character described, the combination with a registering 105 device, of recording mechanism normally inactive, recording mechanism controlling means actuated in synchronism with said registering device, an electric circuit, electro-magnets in said circuit, means for actuating 110 said recording mechanism, and means actuated by said recording mechanism controlling means for closing said circuit.

2. In apparatus of the character described, the combination with a registering 115 device, of recording mechanism normally inactive, recording mechanism controlling means actuated in synchronism with said registering device, an electric circuit, electro-magnets in said circuit, means for actuating 120 said recording mechanism, and means actuated by said recording mechanism controlling means for closing said circuit as said registering device is returned to its initial position.

3. In apparatus of the character described, the combination with a registering device, of recording mechanism normally inactive, recording mechanism controlling means actuated in synchronism with said 130

- registering device, an electric circuit, electro-magnets in said circuit, means actuated by said recording mechanism controlling means for closing said circuit, and means for synchronously actuating said recording mechanism and returning said registering device to its initial position.
4. In apparatus of the character described, the combination with a registering device, of recording mechanism normally inactive, recording mechanism controlling means actuated by said registering device, an electric circuit, electro-magnets in said circuit, means for actuating said recording mechanism, and means actuated by said recording mechanism controlling means for closing said circuit.
5. In apparatus of the character described, the combination with a registering device, of recording mechanism normally inactive, recording mechanism controlling means actuated by said registering device, an electric circuit, electro-magnets in said circuit, means for actuating said recording mechanism, and means actuated by said recording mechanism controlling means for closing said circuit.
6. In apparatus of the character described, the combination with a registering device, of recording mechanism normally inactive, recording mechanism controlling means actuated by said registering device, an electric circuit, electro-magnets in said circuit, means actuated by said recording mechanism controlling means for closing said circuit as said registering device is returned to its initial position.
7. In apparatus of the character described, the combination with a registering device, of recording mechanism normally inactive, an electric circuit, electro-magnets in said circuit, circuit closers, means controlled by said registering device for actuating said circuit closers to energize said magnets to control the operation of said recording mechanism, and means for actuating said recording mechanism.
8. In apparatus of the character described, the combination with a registering device, of recording mechanism normally inactive, an electric circuit, electro-magnets in said circuit, circuit closers, means controlled by said registering device for actuating said circuit closers to energize said magnets to control the operation of said recording mechanism, and means for actuating said recording mechanism as said registering device and circuit closer actuating means are returned to their initial positions.
9. In apparatus of the character described, the combination with a registering device, of recording mechanism normally in-
- active, an electric circuit, electro-magnets in said circuit, circuit closers, means controlled by said registering device for actuating said circuit closers to energize said magnets to control the operation of said recording mechanism, and means for synchronously actuating said recording mechanism and returning said registering device and circuit closer actuating means to their initial positions.
10. In apparatus of the character described, the combination with a registering device, of recording mechanism normally inactive, a series of rotary elements designed to be actuated in synchronism with the registering device while the recording mechanism remains idle or inactive, a shaft upon which said rotary elements are free to rotate in one direction, and means for actuating said recording mechanism as said shaft is rotated to return said elements to their initial positions.
11. In an apparatus of the character described, the combination with a registering device, of recording mechanism having a series of normally inactive type-carrying members, a series of rotary elements designed to be actuated in synchronism with the registering device while the type-carrying members remain idle or inactive, a shaft upon which said rotary elements are free to rotate in one direction, means for actuating said type-carrying members as said shaft is rotated to return said elements to their initial positions, and means controlled by said elements for arresting said type-carrying members.
12. In an apparatus of the character described, the combination with a registering device, of recording mechanism having a series of normally inactive type-carrying members, a series of rotary elements designed to be actuated in synchronism with the registering device while the type-carrying members remain idle or inactive, a shaft upon which said rotary elements are free to rotate in one direction, means for actuating said type-carrying members as said shaft is rotated to return said elements to their initial positions, and means for arresting said type-carrying members as said elements begin their return movements.
13. In apparatus of the character described, the combination with a registering device, of recording mechanism normally inactive, a series of rotary elements designed to be actuated by the registering device while the recording mechanism remains idle or inactive, a shaft upon which said rotary elements are free to rotate in one direction, and means for actuating said recording mechanism as said shaft is rotated to return said elements to their initial positions.
14. In apparatus of the character described, the combination with a registering

end of each series of teeth, said pivoted members being moved out of their normal positions by adjacent type-carrying members, an electric circuit, electro-magnets controlling pawls for engaging said teeth and pivoted members, a series of circuit-closers, a series of rotary members actuated by said registering devices for operating said circuit closers, and means for actuating said recording mechanism and said rotary members in returning said registering devices to their initial positions.

25. In apparatus of the character described, the combination with a registering device, of a series of elements operated in synchronism with said registering device, a series of normally inactive type-carrying members having ratchet teeth, a reciprocating bail for mov-

ing said type-carrying members in one direction, springs for moving them in the opposite direction, an electric circuit having a series of circuit-closers designed to be operated by said series of elements when the latter are being returned to their initial positions, a series of electro-magnets, pawls controlled by said magnets for arresting said type-carrying members, and a striker designed to be actuated in synchronism with the return of said elements to their initial positions.

In testimony whereof, I have signed this specification in the presence of two subscribing witnesses.

HERMAN HOLLERITH.
